SHUTTER OR SIMILAR ARTICLE

Knute B. Norenberg, 1502 10th Ave. S.,
Minneapolis, Minn.

Filed Aug. 7, 1961, Ser. No. 66,219

Term of patent 14 years

(Cl. D13—1)

FIG. 1 is a top plan view of a shutter, showing my new design;

FIG. 2 is a perspective view on an enlarged scale taken from the right front side;

FIG. 3 is a sectional view on an enlarged scale taken along the lines 3—3 of FIG. 1; and

FIG. 4 is a sectional view on an enlarged scale taken along the line 4—4 of FIG. 1.

The dominant features of my design reside in the portions shown in full lines and such full line portions are characterized by the curved concave coving provided on the inner edges of the stiles and end members in combi-

nation with narrow ridges which overlie a portion of the coving on the stiles as well as the portions of the end members which are in abutting relationship with said side stiles.

I claim:

The ornamental design for a shutter or similar article, as shown and described.
